UNITED STATES PATENT OFFICE.

MICHAEL J. HOGAN, OF CHICAGO, ILLINOIS, ASSIGNOR TO THE IMPERIAL BRASS MANUFACTURING COMPANY, OF CHICAGO, ILLINOIS, A CORPORATION OF ILLINOIS.

DESIGN FOR AN ADVERTISING-TABLET.

52,136.

Specification for Design.

Patented July 2, 1918.

Application filed February 21, 1917. Serial No. 150,278. Term of patent 3½ years.

To all whom it may concern:

Be it known that I, MICHAEL J. HOGAN, a citizen of the United States, and a resident of Chicago, in the county of Cook and State of Illinois, have invented a new, original, and ornamental Design for Advertising-Tablets, of which the following is a specification.

To illustrate my invention, I annex hereto a sheet of drawings, in which the figure is a perspective view of the advertising tablet, illustrating my new design.

Copies of this patent may be obtained for five cents each, by addressing the "Commissioner of Patents, Washington, D. C."

I claim:

The ornamental design for an advertising tablet, as shown.

In witness whereof, I have hereunto set my hand and affixed my seal, this 13th day of February, A. D. 1917.

MICHAEL J. HOGAN. [L. S.]
